UNITED STATES PATENT OFFICE.

HAMMOND W. MALLETT, OF SAN DIEGO, CALIFORNIA.

WIRE-STRETCHER.

1,333,865.

Specification of Letters Patent. Patented Mar. 16, 1920.

Application filed July 11, 1917. Serial No. 179,820.

To all whom it may concern:

Be it known that I, HAMMOND W. MALLETT, a citizen of the United States, residing at San Diego, in the county of San Diego and State of California, have invented certain new and useful Improvements in Wire-Stretchers, of which the following is a specification.

My invention relates to wire stretchers more particularly adapted for stretching wire for fences, and the objects of my invention are: First, to provide a wire stretcher that stretches the wire tight so that the wire may be secured to the post upon which the stretcher is supported so that there is no slack in the wire; second, to provide a wire stretcher of this class by the use of which the wire can be stretched as tight as desired regardless of its length without having to secure the wire and take several holds on the same to take care of the slack; third, to provide a wire stretcher of this class which is simple and economical of construction, durable, easy to operate, easy to control, and will not readily deteriorate or get out of order; and fourth, to provide a wire stretcher of this class which is strong enough to stretch the wire to a breaking point if desired.

With these and other objects in view as will appear hereinafter, my invention consists of certain novel features of construction, combination and arrangement of parts as will be hereinafter described in detail and particularly set forth in the appended claim, reference being had to the accompanying drawings and to the characters of reference thereon which form a part of this specification in which:

Figure 1 is a top or plan view of my wire stretcher shown in position on a post which post is shown by dotted lines and showing the wire stretched against the post ready to be fastened thereto; and Fig. 2 is an end elevational view thereof.

Similar characters of reference refer to similar parts throughout the several views of the drawings.

The shaft 1, support 2, collar 3, drum 4, ratchet pawl 5, crank 6, band 7, and chain 8 constitute the principal parts of my wire stretcher.

The support 2 is preferably a metallic piece, flat on one side 2^a so that said support will fit against one side of the post. This support 2 is provided near its opposite side

with a hole therein adapted for a bearing for the shaft 1 in which the shaft 1 is journaled. Secured to said shaft 1 is a collar 3 adapted to rest against the support on one side. Secured to said shaft on the opposite side of said bearing from the collar 3 is the drum 4. The flange 4^a of said drum is provided in its outer edge with ratchet teeth 4^b and said support 2 is cut away approximately the thickness of the outer edge of the flange 4^a to permit the flange of the wheel to revolve in said cut away portion and provides an over-hanging portion upon which the spring pawl 5 is secured, the free end of said spring engaging the ratchet teeth 4^b on the drum 4 for holding the drum in certain position as it is turned. The other flange 4^c of said drum is provided with a notch 4^d adapted for securing the wire therein and when the drum 4 is turned, the wire winds on the drum 4 thus tightening the wire. Each end of the shaft 1 is tapered and preferably rectangularly shaped at 1^b and the crank 6 is provided with an internally tapering socket 6^a adapted to conform to the ends of the shaft 1^b so that said crank may be fitted on either end of said shaft 1, so that the shaft 1 may be turned from either end as desired to suit the convenience of the operator. In some cases where a very large post is used it might be preferable to use the crank next to the drum while in most cases it would be preferable to use the crank on the opposite end. This crank 6 is provided with a handle 6^b to facilitate its turning.

Mounted on the shaft 1 adjacent the long end of said shaft is a band 7 which fits into a groove in said shaft and secured to this band 7 is a chain 8 which is preferably of sufficient length to reach to the next post for supporting the long end of the shaft in stretching the wire.

Though I have shown and described a particular construction, combination and arrangement of parts, I do not wish to be limited to this particular construction, combination and arrangement but desire to include in the purview of my invention, the construction, combination and arrangement substantially as set forth in the appended claim.

It is obvious that with this construction there is provided a wire stretcher for stretching wire for fences in which the wire may be secured to the post against

which the stretcher is supported so that the wire is stretched tight and secured thereto without any slack in the wire. That the wire being wound on the drum provides means for taking up the slack and for making the wire as tight as desired without the necessity of taking several holds of the wire. That the stretcher is supported by the support 2 contacting with the post and the opposite end by a chain secured to the next post or to another post or a stake driven in the ground for the purpose, and that the device as a whole is very simple and economical of construction.

Having thus described my invention, what I claim as new and desire to secure by Letters Patent is:

In a wire stretcher, the combination of a post engaging journal block, a shaft journaled in said journal block provided with a groove near its opposite end and said shaft having square tapered ends, a drum secured to said shaft resting against the one side of said journal block and provided with ratchet teeth on one flange of said drum and with

means for securing one end of the wire to be stretched in the other flange of said drum, a collar on said shaft resting against the opposite side of said journal box from said drum, a spring ratchet pawl secured to said journal box engaging said ratchet teeth whereby said drum and said shaft may be turned in one direction but prevented from turning in the opposite direction, a band in which the groove of said shaft is revolvably mounted, a chain secured to said band extending some distance adapted to be secured to another post in line with the wire to be stretched and passing on the opposite side of said first mentioned post from the side on which the wire is stretched and a handle conforming to the square end of said shaft adapted to be readily connected to either end of said shaft to suit the convenience of the operator.

In testimony whereof I have hereunto set my hand at San Diego, California, this 5th day of July, 1917.

HAMMOND W. MALLETT.
